GERALD J. MCLAREN, OF BALLSTON SPA, NEW YORK

COIN CONTROLLED DOORLOCK

Application filed September 18, 1930. Serial No. 482,833.

This invention is directed to an improvement in coin controlled locks of the type usually applied to various self-service compartments, access to which is had by the user through the deposit of a coin and a subsequent control of the lock of the door following such deposit.

Coin controlled locks of this type are largely used in places accessible to the general public and serve particularly for locks controlling individual toilets, lockers and the like, to which the individual public may be admitted without the necessity of the presence of an attendant, merely by depositing a coin in the locking mechanism to permit control of such locking mechanism by the operator for the single instance of admission, the lock usually automatically locking the door following the exit of the user and requiring a second coin to permit an unlocking operation.

Locks of this type are generally constructed as similar to the conventional key-operated lock, except in the provision of coin controlled means for releasing the locking bolt following the insertion of a coin. Ordinarily the locking bolt and keeper are wholly independent from the coin controlled elements and the knob or handle by which the lock is operated following the release of the lock by the deposit of a coin is also an independent element, to say nothing of the requirement of a coin receptacle to receive the coins after they have performed the lock-releasing function.

These various parts, which are independent one from the other and generally relatively spaced to a considerable extent, present a greater liability of the lock being tampered with or of the coin box being forced open, and to the extent of their independence and relative spacing require the construction and assemblage of a comparatively large number of independent parts, which not only add to the cost of the installation and production, but lend themselves more readily to tampering and unauthorized interference with the proper functioning of the parts.

The primary object of the present invention, therefore, is the provision of a coin

controlled lock of this type in which a single casing element is employed for the reception of the coins, for the operation of the lock, for completely enclosing the locking elements proper, and to serve as a coin box for the reception of the coins following their function in the release of the lock.

A further object of the invention is the provision of a casing of the type noted which shall serve to completely enclose the lock proper, all operating mechanism, and at the same time present a highly ornamental appearance, with entire avoidance of any obstructions of parts which may be tampered with, and so cooperate with the mechanism to be actuated that a partial turning movement of such casing is all that is required on the part of the operator following the introduction of the coin.

A still further object of the present invention is the provision of a coin controlled locking mechanism arranged wholly within and concealed by the casing and serving to normally lock the casing against operative rotation, with such locking means released by the introduction of a coin, and with the locking bolt proper operable in the operative turning of the casing following the proper manipulation by the coin of the casing lock or limiting means.

A further object of the present invention is the arrangement of the keeper and locking bolt for holding the door locked in such relation to the casing that when the latter is in normal position such locking bolt and keeper are entirely concealed and thus not accessible for possible tampering.

The invention is illustrated in the accompanying drawing, wherein:

Figure 1 is a view in broken elevation showing the improved coin controlled locking means applied to a door.

Figure 2 is an enlarged sectional view on the line 2-2 of Figure 4.

Figure 3 is a plan view showing the locking bolt and keeper, together with the means for selectively operating said bolt from the inner side of the door at will.

Figure 4 is a vertical section through the locking means in assembled relation.

Figure 5 is a rear or inner elevation of the casing.

Figure 6 is a broken plan partly in section, illustrating the relation of the keeper for the locking bolt and the hand casing.

Figure 7 is a broken perspective view showing the relation of the locking element to the inner and outer plates.

Figure 8 is a broken perspective view showing the relation of the locking element to the keeper and to the casing.

The improved coin controlled lock is designed to be applied to a door 1 hinged at 2 to the usual door frame 3 to provide a means by which the door is normally locked except following the deposit of a coin which permits the door to be unlocked for the single operation and to be again locked when closed. Of course, in certain uses as, for example, in private toilets, it is desirable that the door shall automatically lock following its initial unlocking through the use of a coin in order that the user may have the desired privacy, and that under these circumstances the door must be capable of being unlocked from within at any desired time. Therefore, the door at a point immediately adjacent one upright of the frame is provided with a spindle 4 rotatively mounted therein and provided on the inner side of the door with the usual knob or handle 5 by which the spindle may be turned.

On the outer side of the door and concentric with the spindle is secured a base plate 6 through which the spindle extends and in which it is freely rotatable. Mounted on this plate 6 is a locking bolt 7 pivotally secured at 8 and having a nose or locking bolt extension 9 at a point below the pivot. A spring 10 secured to the plate 6 overlies and bears upon the locking bolt so as to normally hold the nose 9 projected or in locking relation. The locking bolt intermediate the pivot 8 and nose 9 presents what may be termed a camming edge 11, the curvature of which when the locking bolt is in operative or locking position is substantially coincident with the peripheral edge of the plate 6.

The spindle 4 is provided with a radial pin 12 serving when the spindle is turned through the operation of the knob or handle 5 from the inner side of the door to rock the locking bolt on its pivot and withdraw the nose or projection 9 from locking position. A keeper is carried by the frame 3 of the door comprising a plate 13 secured to the frame and extending above the upper surface thereof and being formed in such extended portion with an opening 14 with which the nose 9 may cooperate for locking the door.

The characteristic feature of the present invention is the utilization of the hand casing, to be later described, as a means for completely enclosing this keeper and thereby the locking nose 9 when the parts are in locked

position. To permit of this result, the plate 6 is peripherally notched at 15 and such plate is so set with respect to the door that the notch of the plate fully receives the keeper so that the latter, when the door is in locked position, does not project at any point beyond the peripheral edge of the plate 6.

Removably secured upon the plate 6 and in spaced relation thereto is a second plate 16. Secured to the plate 16 at the upper extremity of the vertical diameter is a plate section 17 approximately rectangular and appropriately held in spaced relation to the plate 16 to form a coin-receiving space 18 fully open at the top and bottom. Pivots supported at 19 on the plate 16 is a locking lever 20. This locking lever is in the form of a bar pivotally mounted off center, with the shorter end 21 projecting into the coin space 18 and having its terminal edge sharply inclined, as indicated at 22. The opposite or longer end 23 of the lever 20 terminates in a sharply inclined edge 24, and a spring strip 25 terminally secured, for example, to the plate section 17 and bearing beneath the locking lever tends to hold the latter in a predetermined position. This predetermined position of the locking lever is such that the free point or terminal of the portion 23 of the lever is substantially coincident with the peripheral edge 20 of the plate 6, while the inclined edge 22 of the short end of the lever rests in the path of a coin passing into the coin space. In this position the lever will be engaged by any coin passed into the coin space, for a purpose which will be later explained.

It will be remembered that the lever 20 is pivotally supported by the plate 16, and as the terminal 24 of this lever is to have a locking function in connection with the hand casing to be later described, the plate 16 throughout a considerable margin of its peripheral edge on both sides of the free terminal of the lever 20 is cut away, as at 26, in order that in the normal position of the lever 20 the free terminal 24 may project beyond the edge of the plate 16 formed by this cut away portion. The peripheral margin of the plate 16 including and extending in most directions beyond the cam edge 11 of the locking bolt 7 is also cut away at 27, exposing such cam edge for operative control in the movement of the hand casing, as will later appear.

Secured upon the plate 16 coaxially with the spindle 4 is a sleeve 28 open at the outer end and formed with diametrically opposed notches 29. Arranged axially of this sleeve and forming a part thereof is a center post 30 of less length than the sleeve and terminally threaded at 31.

The important detail of the present invention is what may be termed the hand casing, which is so constructed as to completely enclose all operating parts including the nose 130

of the locking bolt and the keeper therefor, which serves as a means or handle for operating the locking bolt to disconnect it from the keeper to permit opening of the door, 5 which serves as a means for releasing the coin from the coin control mechanism following the unlocking function of the coin, and which serves as a coin box for receiving and retaining the coins after their cooperation with 10 the locking means. This hand casing, indicated at 32 and shown more particularly in Figure 4, is in the form of a hollow body including a peripheral wall 33 and enclosed top 34 of appropriate ornamental configuration, 15 if desired, and fully open at the bottom or inner end. The internal diameter of the peripheral wall 33 of the hand casing corresponds approximately to the diameter of the plate 6 so that in applied position the peripheral edge of the plate 6 is seated within the hand casing and the latter is in effect guided 20 on the peripheral edge of the plate 6.

The upper portion of the wall 33 at an appropriate point is offset at 35 and formed in 25 such offset with a slot 36 serving the function of a coin slot for the introduction of a coin and designed, when the hand casing is in normal or inoperative position, to be in vertical registry with the coin-receiving space 18 formed by the plate 16 and plate section 17, 30 as previously described. The normal position of the hand casing is insured through the medium of a coil spring 37, one terminal of which is secured to the plate 16 and the other terminal of which is removably engaged with a pin 38 projecting from the inner surface of the wall 33. The removable connection of the spring permits the convenient detachment of the hand casing when necessary to inspect, repair or renew the locking parts.

Projecting from the inner surface of the wall 33 in that portion substantially in the plane of the peripheral edge of the plate 16 is a locking lug 39, and arranged immediately adjacent this lug and outwardly therefrom with respect to the plate 16 is a release lug 40 terminating in an inwardly inclined lip 41 which is arranged beyond the terminal of the lug 39 in the direction of rotation of the hand casing. Also projecting inwardly from the wall 33 of the hand casing about centrally of the coin slot 36 is a locking bolt actuator in the form of a lug 42. This lug 45 is so arranged with respect to the wall of the hand casing that its path of movement is in the plane of the cam edge 11 of the locking bolt, the radial extension of the lug being such as to rock the locking bolt when such 50 lug rides over the cam edge 11 to thereby swing the locking bolt in a direction to withdraw the nose 9 from the keeper opening 14.

The hand casing is secured to the plate 16 through the medium of a locking sleeve 43 having an exterior diameter to fit within the

sleeve 28, the lower end of the sleeve being threaded for cooperation with the threaded terminal 31 of the post 30. The locking sleeve 43 is provided with tumblers 44-44 controlled by an appropriate key 45 introduced through a key slot 46 in a disk terminal 47 forming the outer end of the sleeve 43 and overlying the top 34 of the hand casing 32 to conceal the opening through which the locking sleeve 43 is introduced. The arrangement of the tumblers 44 is unimportant and needs no further description or showing beyond the fact that they are arranged so that on inward movement of the key the tumblers are withdrawn to the peripheral plane of the locking sleeve 43 so that the locking sleeve 43 is free to turn in the sleeve 28 until the threaded cooperation of such sleeve 43 and post 30 is such as to arrange the hand casing substantially against the surface of the door surrounding the peripheral edge of the plate 6 with the disk 47 overlying and bearing upon the top of the hand casing.

On the removal of the key, the tumblers 44 act under appropriate spring pressure to move outwardly into the recesses 29 in the sleeve 28 secured to the plate 16. Thus the hand casing is mounted for free rotary movement with respect to the plates 6 and 16 but held against independent axial movement with respect thereto.

In the normal position of the parts, that is, with the coin slot 36 in the hand casing in alignment with the coin-receiving space 18, the locking lug 39 is in the plane of the projecting end 24 of the locking lever 20 so that while a limited movement of the hand casing is permitted, this movement is insufficient to carry the locking bolt actuator 42 to a position to engage the cam edge 11 of the locking bolt. On the introduction of an appropriate coin, indicated at 48 in Figure 2, through the coin slot 36 in the hand casing and into the coin space 18 between the plate 16 and plate section 17, the coin by riding into contact with the inclined end 22 of the locking lever 20 rocks this inclined end upwardly and outwardly, thus withdrawing the terminal 24 from the path of movement of the locking lug 39. The hand casing may now be turned until the locking bolt actuator 42 wipes over the cam edge 11 of the locking bolt, swinging the locking bolt on its pivot 8 and withdrawing the locking nose 9 from the keeper opening 14, whereupon and in the substantially continuous movement the door may be opened by the use of the hand casing as a handle or knob in the usual manner.

During the movement of the hand casing after the introduction of the coin and before the locking bolt actuator 42 reaches the cam edge 11 of the locking bolt 7, the inclined extension 41 of the release lug 40 wipes over the end of the locking lever 20 and moves

the lever somewhat farther or to a greater extent than and in the same direction as such lever is moved on the introduction of a coin. The coin, which has been momentarily retained in position by the bearing against such coin of the end 22 of the locking lever, is thus free of the holding influence of the locking lever such coin drops freely through the coin space 18 and into the lower portion of the hand casing.

On the return of the parts to normal position which is a result of the operation of the spring 37, the lugs 39 and 40 are arranged below the free terminal of the locking lever 15 in a direction beyond the coin slot and the locking lever has been returned to normal or locking position which it normally maintains in the absence of a coin. The hand casing is thus locked against that rotative movement necessary to operate the locking bolt and the parts are arranged for a subsequent operation. Of course, the locking bolt is free to move to and from locking position against the tension of the spring 10 so that 20 as the door is closed the locking bolt accommodates itself to the movement and re-locks the door by entering the keeper. The locking nose 9 is appropriately beveled to permit its displacement when cooperating with the keeper plate 13 in the closing of the door. The door may be unlatched or unlocked from the inner side through manipulation of the knob or handle 5 at any time.

The important characteristic feature of 35 the present invention is the single hand casing serving as a knob for opening and closing the door, serving as a means to receive and temporarily retain the coin, serving as a means to operate the locking bolt following 40 the release of the locking mechanism by the coin, serving as a means to effectually conceal all operating parts including the lock, locking bolt and keeper, and serving further as a means for retaining the coins 45 after their function in releasing the locking mechanism for the hand casing. Thus the single hand casing performs the several functions usually performed by separate and wholly independent parts in previous 50 coin controlled locks, and aside from presenting a very much more ornamental and desirable appearance, provides in a single element the operative and protective functions, rendering the lock fool-proof, practically incapable of being tampered with, and protecting the deposited coins against 55 unlawful abstraction. The mechanism of the lock for the deposited coins is accessible at any time through the use of an appropriate key serving to withdraw the tumblers 44 and permit disconnection of the sleeve 43 and post 30, whereupon the casing may be freely and entirely removed subject to the disconnection of the spring 37 from the hook 60 38.

It is to be particularly understood that while the coin controlled locking means herein described defines a simple and desirable construction for use in connection with the hand casing, the invention contemplates the use of any preferred or appropriate type of coin controlled mechanism constructed and arranged to permit the desired operation of the hand casing.

I claim:—

1. A coin controlled lock for doors and the like including a door locking element, a hand casing mounted for rotation, means carried by the casing to operate said element, and coin controlled means for normally preventing such rotative movement of the hand casing, said casing serving as a coin receptacle for the reception of the coins following their cooperation with the coin controlled locking means.

2. A coin controlled lock for doors and the like including a locking element for the door, a hand casing mounted for rotation, means carried by the casing and operative in such rotation to operate the locking element, coin controlled locking means normally preventing rotation of the hand casing to a degree necessary to operate the locking element, said hand casing overlying and protecting the locking element against tampering.

3. A coin controlled lock for doors and the like including a locking element for the door, a hand casing mounted for rotary movement with respect to the door, means carried by the casing and operative in such casing movement to cooperate with the locking element, a locking lug on the hand casing, a member normally in the path of the lug to prevent rotative movement of the casing, said member being displaceable on the introduction of a coin beyond the path of the lug to permit that rotative movement of the casing necessary to influence the locking element.

4. A coin controlled lock for doors and the like including a locking element for the door, a hand casing mounted for rotary movement with respect to the door, means carried by the casing and operative in such casing movement to cooperate with the locking element, a locking lug on the hand casing, a member normally in the path of the lug to prevent rotative movement of the casing, said member being displaceable on the introduction of a coin beyond the path of the lug to permit that rotative movement of the casing necessary to influence the locking element, said member when displaced by the coin serving to retain the coin in the then position, and means carried by the casing to further operate the member to release the coin.

5. A coin controlled lock for doors and the like including a locking element for the door, a hand casing mounted for rotary movement with respect to the door, means carried by

the casing and operative in such casing movement to cooperate with the locking element, a locking lug on the hand casing, a member normally in the path of the lug to prevent rotative movement of the casing, said member being displaceable on the introduction of a coin beyond the path of the lug to permit that rotative movement of the casing necessary to influence the locking element, said member when displaced by the coin serving to retain the coin in the then position, and means carried by the casing to further operate the member to release the coin, said casing being at all times in position to receive and retain the coin following release of the coin.

6. A coin controlled lock including a locking element, a hand casing rotative with respect to the element, means on the interior of the casing to engage and operate the element in the rotative movement of the casing, a locking lug on the casing, and coin controlled means for normally cooperating with the lug to prevent rotative movement of the casing, said means being displaceable by a coin to avoid interference with the lug whereby to permit rotative movement of the casing to operate the locking element.

7. A coin controlled lock including a locking element, a hand casing rotative with respect to the element, means on the interior of the casing to engage and operate the element in the rotative movement of the casing, a locking lug on the casing, and coin controlled means for normally cooperating with the lug to prevent rotative movement of the casing, said means being displaceable by a coin to avoid interference with the lug whereby to permit rotative movement of the casing to operate the locking element, the casing being positioned to overlie and conceal said coin control means and locking element.

8. A coin controlled lock for doors and the like including a locking element mounted on the door, a keeper for the locking element mounted on the part with which the door cooperates, a hand casing mounted for movement with respect to the door and operative to engage and operate the locking element to withdraw it from the keeper, and coin controlled means for governing the movement of the hand casing, said hand casing enclosing and concealing the coin controlled locking means, the locking element and the keeper.

9. A coin controlled lock for doors and the like including a locking element mounted in the door, a hand casing rotative with respect to the door, means carried by the casing to engage and operate the locking element, coin controlled means arranged within the casing to normally prevent operative movement of the casing, said coin controlled means serving in the presence of a coin to retain the coin during the initial movement of the hand casing, and means on the hand casing to influence the coin controlled means to release

the coin, said casing serving as a coin receptacle for the released coins.

10. A coin controlled lock for doors and the like including a locking element mounted in the door, a hand casing rotative with respect to the door, means carried by the casing to engage and operate the locking element, coin controlled means arranged within the casing to normally prevent operative movement of the casing, said coin controlled means serving in the presence of a coin to retain the coin during the initial movement of the hand casing, means on the hand casing to influence the coin controlled means to release the coin, said casing serving as a coin receptacle for the released coins, and means whereby the casing is automatically returned to normal position when released and following the operation of the locking element.

11. A coin controlled locking means for doors and the like including locking elements to hold the door fixed with respect to the member with which it cooperates, coin controlled means, and a casing mounted for rotary movement with respect to the door and normally held against movement by the coin controlled means, said casing when released by the coin controlled locking means serving to operate the locking elements to release the door, said casing serving as a hand hold for operating the door and as a concealing means for the coin controlled means and locking elements.

In testimony whereof I affix my signature.
